A. A. Lincoln, Jr. of Norton, Mass.
Letters Patent No. 751. Dated Dec. 18, 1853.

The schedule referred to in these Letters Patent and making part of the same.

To all Persons to whom these Presents shall come:

Be it known, that I, A. A. Lincoln, Jr. of Norton, in the county of Worcester and State of Massachusetts, have produced a new and original design for a ship's Babooe Stone, and I hereby declare, that the said new design is fully described and represented in the following Specification and accompanying drawings to which reference is hereinafter made.

The figures of the accompanying plate of drawings represent my new design. —

In Plate 1, Fig. 1, is an elevation of the front plate of the stone.

Fig. 2, is a section of the same taken in the plane of the line A B, fig. 1.

In Plate 2, Fig. 3, is an elevation of the side plate of the stone.

Fig. 4, is a section of the same taken in the plane of the line C D.

The front plate Figs 1 and 2, plate 1, is ornamented with the flat bar moldings a, a, &c and ornamented rivets b, b. The oven door c, c, and fire chamber door d, d, are each ornamented with the moldings e, e, and bead moldings f, f.

The upper corners of the front plate have on them the diamonds g, g, with a rivet b, in the center of each. The side plate Figs. 3 and 4, plate 2, has on it the bar moldings a, a, rivets b, b, diamonds g, g, and the ornamental bead or scalloped moldings h, h.

Having thus described my improvements, I shall state my claims as follows:

What I claim as my invention or production, is the new design for a cooking Stone, consisting of the bar moldings, rivets and bead or scalloped molding, as herein above described and represented in the drawings.
